(57) **CLAIM**

The ornamental design for an LED headlight, as shown and described.

DESCRIPTION

1. LED headlight

1.1 is a perspective view of an LED headlight in accordance with our new design;

1.2 is a front elevational view thereof;

1.3 is a rear elevational view thereof;

1.4 is a right side elevational view thereof;

1.5 is a left side elevational view thereof;

1.6 is a top plan view thereof; and

1.7 is a bottom plan view thereof.

The broken lines showing portions of the article form no part of the claimed design.
